UNITED STATES PATENT OFFICE.

WILLIAM B. NORTH, OF NEW HAVEN, CONNECTICUT, ASSIGNOR TO O. B. NORTH & CO., OF SAME PLACE.

DESIGN FOR HARNESS-TRIMMING.

SPECIFICATION forming part of Design No. 12,030, dated November 9, 1880.

Application filed September 11, 1880. Term of patent 7 years.

To all whom it may concern:

Be it known that I, WM. B. NORTH, of New Haven, in the county of New Haven and State of Connecticut, have invented a new Design for Hook and Terret; and I do hereby declare the following, when taken in connection with the accompanying drawings and the letters of reference marked thereon, to be a full, clear, and exact description of the same, and which said drawings constitute part of this specification, and represent, in—

Figures 1 and 2, side views of the hook and terret; Fig. 3, an edge view of the same.

This invention relates to a design for the articles of saddlery hardware which are attached in sets to the harness-saddle, commonly called "terret and water hooks;" and the design consists in the configuration of the article, as hereinafter described, and shown in the accompanying illustration.

The shape of the base and of the interior of the hook and terret is immaterial; but on the outside they present a convex shape in transverse section for a part of their circumference and flat the remainder. In the illustration of the lower portion, from the base *a* to about one-

half the height, or to the point *b*, the exterior is convex in transverse sections, as is more clearly seen in Fig. 3.

From the point *b* on one side to the corresponding point on the other the surface is comparatively flat, the convex surface dying out in the flat surface, making a clearly-defined line, as at *b*, where the two differently-shaped surfaces meet. In the case of the hook it will be understood that the opening breaks the surface at the upper part, yet presents the same exterior peculiarity.

The two different shapes—that is, flat and convex surfaces—may be reversed—that is to say, flat below and convex above.

I claim—

The design for hooks and terrets, consisting of the flat surface over one portion and convex over the remainder, running into each other and forming a defined line, *b*, on the sides, substantially as described, and shown in the accompanying illustration.

WM. B. NORTH.
